UNITED STATES PATENT OFFICE.

JAMES J. SLEVIN, OF NEW YORK, N. Y.

BICYCLE-FORK.

SPECIFICATION forming part of Letters Patent No. 674,744, dated May 21, 1901.

Application filed May 12, 1898. Renewed October 17, 1900. Serial No. 33,404. (No model.)

To all whom it may concern:

Be it known that I, JAMES J. SLEVIN, a citizen of the United States, residing at New York, in the county and State of New York, 5 have invented a new and useful Improvement in Bicycle-Forks, of which the following is a specification.

Bicycle-forks are usually made hollow or, in other words, of tubular construction, and 10 it occasionally happens as the result of a fall or collision that said forks become dented, bent, or broken and cause inconvenience to the wheelman. This sometimes happens at a distance from home or from a shop where 15 repairs can be made; and the object of my invention is to lessen the risk of such difficulty and inconvenience.

In carrying out my invention I employ in connection with and in addition to the usual 20 tubular bicycle-fork an auxiliary emergency-fork and fork-crown placed within and adjacent to the tubular fork, the lower ends of such auxiliary emergency-fork having openings or notches to receive the axle of the front 25 wheel, and the upper end of the fork-crown having a stem to pass into the hollow steering-post connected to the ordinary fork. This auxiliary emergency-fork is preferably 30 solid and composed of spring-steel, and being connected at the top of the steering-post and at the fork ends to the axle of the wheel will if either or both the tubular-fork sides become accidentally broken or otherwise injured take the place of the same in supporting 35 the rider and guiding the wheel and will also lend an additional support to the ordinary fork, lessening the risk of accident.

In the drawings, Figure 1 is an elevation, partially in section, illustrating my improvement. Fig. 2 is a sectional plan at the line 40 $x-x$ of Fig. 1. Fig. 3 represents a vertical section of a modification, and Fig. 4 is a section at the line $y-y$ of Fig. 3.

The tubular front-fork sides are shown at 45 $a-a'$, the fork-crown at b , the steering-post at c , and the handle-bar stem at d , the front hub at e , and the axle at f , the cones at $g-g'$, and the nuts at $i-i'$. These parts are all of usual and well-known construction and do 50 not require further description.

The auxiliary emergency-fork sides are shown at $l-l'$ and their fork-crown at m .

These sides are within, adjacent to, and extend throughout the length of the usual-fork sides $a-a'$ and crown b of the bicycle. They 55 are preferably solid and composed of spring-steel, the crown part being thickest and the sides tapering toward the fork ends $3-4$, which are each provided with an opening or a notch to receive the axle f of the front wheel. 60

The upper end of the fork-crown m is provided with a tubular head o to pass into the central opening of the fork-crown b or the base of the steering-post c . This head is supposed to fit tightly in place, so as not to turn 65 or to be accidentally loosened or disconnected by the bending or breakage of either of the front-fork sides $a-a'$.

I prefer to make the fork-crown m with a direct connection to the handle-bar stem and 70 to that end employ a stem r , having a rectangular tenon on the upper end, the said stem passing upward through the steering-post c , and I prefer to make the lower end of the handle-bar stem d with a plug having a 75 central rectangular opening for the rectangular tenon that fits and is received in the said rectangular opening in the plug at the lower end of the handle-bar stem. The object of this is to form a more secure and positive bearing for the auxiliary fork and connection therefrom to the handle-bar stem and 80 independent of the frictional connection with the base of the steering-post or the fork-crown b . With this construction a direct connection is effected between the axle of the 85 front wheel and the handle-bar stem, so that the one part cannot turn without the other. Consequently if the usual collar employed for clamping the handle-bar stem to the steering-post should accidentally loosen or be neglected no harm can arise, as the cycle will 90 still be under control of the handle-bars.

I prefer to make the auxiliary emergency-fork sides fit snugly along and against the 95 inner surfaces of the ordinary-fork sides and to curve the lower ends of the auxiliary emergency-fork sides to assist this condition and obviate any tendency to vibrate and cause a rattling noise.

The emergency-fork and crown can be added to cycles already in use and can be removed with facility after being in place, if necessary for any cause.

I am aware that bicycles have heretofore been made with two forks; but in this case a different object was sought and one fork was pivotally connected to the front-wheel axle, 5 and the steering-post of the bicycle was provided with a spring against which one fork bore, so that the forward part of the bicycle was provided with a spring-action to lessen the vibration incident to concussion in riding; 10 but said object and condition are totally different from my invention.

I claim as my invention—

1. In a bicycle, the combination with the steering-wheel, its axle, the front fork, the 15 crown and steering-post, of an auxiliary emergency-fork within and adjacent to the usual fork and integral with a fork-crown and provided with a head adapted to pass forcibly 20 into the usual fork-crown that is connected with the steering-post and with openings at

the lower fork ends for connection to the axle of the front wheel, substantially as set forth.

2. In a bicycle, the combination with the front wheel, its axle, the front fork, the crown, the steering-post and the handle-bar stem, of a 25 plug in the lower part of the handle-bar stem having an opening therein, an auxiliary emergency-fork of metal and a crown made integral therewith, a stem connected to the crown passing through the steering-post and 30 at its upper end entering the plug in the lower part of the handle-bar stem and the lower fork ends receiving through them the axle of the front wheel, substantially as and for the purposes set forth.

Signed by me this 9th day of May, 1898.

JAMES J. SLEVIN.
